ATTORNEYS

UNITED STATES PATENT OFFICE.

JESSE PERKINS MILLER, OF HOUMA, LOUISIANA, ASSIGNOR OF ONE-HALF TO J. H. THATCHER, OF HOUMA, LOUISIANA.

EXPANSIVE DRILL BIT.

Application filed August 3, 1921. Serial No. 489,522.

To all whom it may concern:

Be it known that I, JESSE PERKINS MILLER, a citizen of the United States, and a resident of Houma, in the parish of Terrebonne and State of Louisiana, have invented certain new and useful Improvements in Expansive Drill Bits, of which the following is a specification.

My invention relates to improvements in expansive drill bits, and it consists in the constructions, combinations and mode of operation herein described and claimed.

One of the foremost objects of the invention is to provide a drill bit, the blade of which expands or spreads when weight is imposed thereon.

A further object of the invention is to provide a drill bit including a holder or collar formed with a socket provided with a slot and such an arrangement of bevels that the blades are caused to spread when slid up the slot, to drill a hole larger than the diameter of the casing in which the drill operates.

Other objects and advantages will appear in the following specification, reference being had to the accompanying drawings in which:

Figure 1 is a side elevation of the improved expansive drill bit, the blades being shown hanging in the normally collapsed position.

Figure 2 is a section on the line 2—2 of Figure 1, showing the blades collapsed in full lines and spread in dotted lines, the latter position being assumed when weight is imposed on the bit.

Figure 3 is a sectional perspective view illustrating the position assumed by one of the blades when weight is imposed on the bit.

Figure 4 is a plan view of the upper end of the bit collar, showing the drilling water hole, and

Figure 5 is a detail horizontal section on the line 5—5 of Figure 2.

It is one of the principal purposes of the invention to provide a drill bit, the blades of which will expand or spread when weight is imposed thereon, thereby to drill a hole of a diameter larger (or at least as large) as the casing in which the bit works. In Figure 2, the blades 1 and 2 are each provided with opening bevels 3 and 4. When

the lower extremities of the blades strike the bottom of the hole, they naturally stop, and as the weight of the holder or collar 5, and other superposed parts, descends upon the blades, the opening bevels 6 at the sides of the slot 7 engage the bevels 3 and 4, and cause the blades 1 and 2 to spread from the full line position to the position shown in dotted lines.

It is wholly by means of the weight imposed on the bevels 3 and 4 that the blades 1 and 2 are caused to spread as stated. Each blade is also provided with a beveled shoulder 8 and 9 for the purpose of resting against the bevels 6 and providing solid supporting shoulders to receive the thrust imposed on the blades. The slot 7 is of rectangular formation, as shown in Figure 5, so as to snugly contain the upper parts or shanks 10 of the blades. It is intended that there shall be no excessive loose motion of the shanks, and the slot 7 may be filled with grease for the purpose of lubricating the moving parts and at the same time excluding water and dirt in a large measure.

A pivot pin 11 holds the blades together. Pins 12 retain the blades on the collar 5. The upper end of each shank 10 is provided with shoulders 13 which engage the pins 12 at the respective sides and keep the blades from dropping out of the slot 7 when they assume the normal collapsed position. A groove 14 below each of the shoulders, provides room for the upward movement of the blades past the retaining pins 12. The collar 5 is provided with holes 15 through 19 which drilling water passes to the point of operation of the blades 1 and 2.

The operation may be briefly reviewed to advantage. In letting the drill bit down into the casing, the blades 1 and 2 hang as shown in full lines in Figure 2. They are pivoted together by the pin 11. The blades are so proportioned that they hang together, their lateral edges lying flush with each other.

Imagine the collar 5 moving down upon the blades, and the blades as having been stopped by the bottom of the hole. The bevels 6 will first engage the opening bevels 3 and 4 of the blades and cause the latter to spread, the blade 1 toward the right and the blade 2 toward the left, until they finally assume the dotted line position. Each blade

has a straight side 16 opposite its opening bevel, to accommodate the spreading action just described. Any type of blade may be used in the collar 5; fishtail, diamond point, 5 drag, or rollers or discs. The fishtail type of blade (shown in the drawing) is the most common and useful shape. The advantage of employing the principle of operation intended to be employed in connection with 10 this bit (the superposition of weight on the bit blades) is to insure the cutting of a hole larger than the diameter of the casing and keeping that diameter relatively uniform. The wear on the blades and consequent re- 15 duction in the diameter of the hole as the depth increases, is compensated for by the initially larger diameter of the hole. Therefore there is little danger of drilling the hole smaller than the casing with the consequent difficulty of having the casing bind 20 when driven farther.

While the construction and arrangement of the improved expansive drill bit as herein described and claimed, is that of a generally 25 preferred form, obviously modifications and changes may be made without departing from the spirit of the invention or the scope of the claims.

I claim:—

30 1. A drill bit comprising a holder provided with a socket opening through one end thereof and having a slot formed through its walls at the edge of the socket, said slot being provided with a bevel, and a drill 35 blade having the shank thereof slidably disposed within the socket and being provided with a bevel adapted to engage the bevel of the slot to occasion a lateral movement of the free end of the blade when the weight 40 of the holder is superimposed upon the blade.

2. A rotary drill bit, comprising a collar with a slot having opening bevels, and a 45 pair of blades each having an opening bevel in line with those of the slot to be engaged

by the latter when the collar moves down, to spread the blades by its weight.

3. A rotary drill bit, comprising a casing having a slot with lateral opening bevels, blades pivoted to normally hang together in 50 the collapsed position, each having a bevel on one side and a straight portion on the other, the bevels and straight portions being on opposite sides of the respective blades, the bevels of the slot engaging those of the 55 blades when the collar moves down to spread and lock the blades; and means associated with the slot and blades to limit the separating movement of the blades and collar.

4. A rotary drill bit, comprising a collar 60 with a slot having opening bevels on opposite sides, a pair of blades with shanks extending into the slot and pivoted at the top, shoulders formed adjacent the top of the shank, retaining pins traversing the slot to 65 support the blades when normally collapsed, and an opening bevel on one side of each blade, with a straight portion on the opposite side of the same blade, said opening bevels being engaged by those of the collar 70 when the latter is let down, to spread the blades beyond the circumference of the collar.

5. A drill bit comprising a holder provided with an axial socket opening through 75 one end thereof and having a pair of longitudinally extending slots formed through its walls at opposite sides of the edge of the socket, each of said slots being provided with a bevel, and a pair of drill blades having the shanks thereof slidably supported 80 within the socket and having bevels at the opposite sides thereof respectively adapted to engage the corresponding bevels of the said slot when the weight of the holder is 85 superimposed upon the blades to occasion the spreading of the blades at their outer ends.

JESSE PERKINS MILLER.
